UNITED STATES PATENT OFFICE.

JACOB SODERBERG, OF PITTSBURGH, PENNSYLVANIA, ASSIGNEE TO PITTSBURGH PLATE GLASS COMPANY, A CORPORATION OF PENNSYLVANIA.

HEADLIGHT GLASS OR LENS.

Application filed February 8, 1921, Serial No. 443,362. Renewed November 17, 1923.

To all whom it may concern:

Be it known that I, JACOB SODERBERG, a citizen of the United States, and a resident of Pittsburgh, in the county of Allegheny and State of Pennsylvania, have made a new and useful Invention in Headlight Glasses or Lenses, of which the following is a specification.

The invention relates to headlight glasses or lenses for use upon vehicles and particularly upon automobile lamps. The invention has for its principal objects the provision of a lens, which, (1) when used with the usual parabolic reflector, will give a field of illumination of the desired range of intensity, free from black spaces or lines, and in which the light may be distributed to the best advantage, and in accordance with the generally accepted requirements of the various States, and (2) in which the prism surfaces are of such a character that the mold for producing them may be made or refinished by machine work (rather than by hand chipping), thus producing mathematically accurate surfaces more cheaply and in a material such as stellite or ni-chrome, which is superior for glass casting or mold work and which otherwise could not be utilized because of the difficulty of working it. Other objects and advantages incident to the lens will be apparent from the accompanying description and illustrations. One embodiment of the invention is illustrated in the accompanying drawings, wherein:

Figure 1 is a rear elevation of the lens; Fig. 2 is a horizontal section on the line II—II of Fig. 1; Fig. 3 is a vertical section on the line III—III of Fig. 1, and Fig. 4 is a diagonal section on the line IV—IV of Fig. 1.

The idea involved in the construction of the improved lens is to start as the basis of the design with a lens having concentric annular ridges or prisms, which is the equivalent of a plano-concave lens, and modify the angles of the prisms so as to get the desired distribution of light which is required for automobile or headlight work. Such a lens (before the present improvement is applied thereto) when used with a parabolic reflector, spreads the light away from the center or axis of the parabola in all directions.

As the first step in the design the angles

of the annular prisms are made such that, in so far as the lateral dispersion of light is concerned, just the right amount is secured for giving the required side lighting. This dispersion, however, is, of course, not right in so far as the upward and downward dispersoin is concerned, and particularly with respect to the upward dispersion as it is necessary that the transmitted light should not produce an objectionable glare above a certain level, and further, any light transmitted above that level would be more or less wasted since it would be of no effect in illuminating the roadway. The angle of the prisms must therefore be so modified as to turn the light downwardly, and this is accomplished in my invention by dividing the annularly ribbed lens into horizontal bands or sections, and tilting the sections of the annular prisms in the bands in such way as to bring the light transmitted through each band at the desired level.

This tilting of the various sections or bands must be made somewhat greater than would be theoretically called for with a perfect reflector and with the light condensed to a point and located at the focus of the parabola. The light filament lies both to the front and rear of the reflector focus so that there is an upward and downward dispersion of the light away from the horizontal plane along which a beam of light would be theoretically transmitted. The bands are therefore tilted to bend the rays downward to a greater extent than would be the case if the light were concentrated at a point at the focus of the reflector, and this is particularly the case with the central bands, as the central portion of the reflector gives a greater divergence of rays due to the character of the filament than does the outer portions of the reflector.

The angle of tilting of the bands must be determined to a certain extent by experiment, due to the condition as above stated with respect to the light filament, so that the theoretical tilting of the various bands may not conform to that actually required, and the invention is not limited to the tilting of the successive bands according to any fixed rule. In general, the amount of tilting in the various bands from the center, both up and down, will decrease, although in some cases it might be desirable to make the tilting the same in certain bands. The faces

of the prisms upon the rear side of the lens are preferably made curved instead of straight, as this causes the bands of illumination to overlap and blend to better effect than when prisms with flat faces are used, thus assisting in eliminating black lines or shadows from the field of illumination.

The plunger for producing the ribbed surface of the lens in the pressing operation can be formed upon a planer or milling machine used in conjunction with a lathe. In order to do this, grooves of the desired angle of tilting are first planed or milled in a supporting fixture, after which strips of metal rectangular in cross section are fitted into the grooves and machined to a plane surface upon their rear faces. After this the annular grooves are turned or ground in a lathe upon the plane surface as above produced. The annular strips are then removed and the sides of the strips opposite to the side carrying the annular grooves are secured to a flat surface constituting the body portion of the plunger. The ability to produce this plunger by machine work is a great advantage since it permits the plunger to be made of excessively hard material, such as stellite or nichrome. These materials will last a long time in casting operations without requiring re-surfacing, and the material, because of its smoothness and durability, gives a better surface to the glass than is the case with the cast iron mold. These are advantages not possessed by molds of such irregular contour that they must be formed by hand chipping and working. Such molds must necessarily be of relatively soft composition, such as cast iron. Molds of such material require frequent re-surfacing, involving a large item of expense, and in many cases changing the angles of the prisms.

Referring now to the drawings, 1 is the edge or holding portion of the lens for fitting into the casing of the lamp, and 2, 3, 4, 5 and 6 (Fig. 2) are annular prisms or ridges which divide the rear face of the lens into a plurality of annular bands. As indicated in Fig. 2, which shows the normal angle of the prisms, that is the angle before the tilting in horizontal bands heretofore referred to, such prisms are at sufficient angle to bend the parallel rays from a parabolic reflector passing therethrough, outwardly, to give the necessary side lighting. In order to give this dispersed light the necessary downward inclination to avoid glare and get the desired illumination on the roadway, the rear face of the lens is divided into the horizontal bands 7 to 17; this division as to number of bands being purely arbitrary and subject to change, depending upon the size of the lens required and upon the character of the distribution desired, as well as other practical considerations. These bands are tilted at varying angles as will be seen from Fig. 3,

such angles decreasing from the center of the lens up and down. The increased angle at the center is due to the fact that a part of the central rays diverge more than those rays from the outer portion of the reflector. This is caused, as heretofore referred to, by the character of the filament employed, which of necessity cannot be concentrated at the focus of the reflector but extends forward and backward of such focus and causes a divergence of the rays from all portions of the lens from the horizontal but at an exaggerated degree from the portions of the reflector nearest the center. This point is most important in connection with the angle of the bands above the axis A of the lens and of the reflector, since these upwardly diverging rays are most objectionable because of the glare produced, while the rays from the lower half of the lens are bent downwardly anyway because of the inclination of the annular prisms, but at the same time the bending of the light passing through the lens just below the center is important since the lateral dispersion is so great that the side illumination from such portion of the lens is too far to the side and has little utility. By bending this light down sharply it is brought closer to the car and nearer to the center of illumination.

The angles as illustrated in the various sections are exaggerated in order to more clearly illustrate the principle involved, which principle, as well as the peculiar and varying angles, will be readily understood by an inspection of Fig. 3 in connection with Fig. 4, the latter being taken on the diagonal plane IV—IV of Fig. 1. It will be seen that the amount of tilting from the normal of the various annular sections lying within any horizontal band is the same. For instance, the annular sections 9^a, 9^b, 9^c, 9^d and 9^e, lying in the horizontal band 9 are all swung from their normal angle the same amount, which is a different amount from that which the sections lying in the adjacent horizontal bands 8 and 10 are tilted. This breaks the face of the lens into a very large number of lenses of varying angles, accomplishing, in addition to the function of bending the light downwardly the desired amount, the further function of eliminating any tendency to black spaces or lines in the field of illumination. The transmitted light from the various adjacent sections overlap and mingle to a certain extent, and this diffusion and overlapping is increased by reason of the curvature of the faces of the annular prisms, as indicated most clearly in Figs. 2 and 3. Any tendency, therefore, in the transmitted light to cause individual bands, distinguishable from each other in the field of illumination, is avoided.

As heretofore indicated, the angles of the surfaces of the molds may be produced by

machine work, and can be made with mathematical accuracy so that an exact result may be secured, and in refinishing this same result may be secured. The angles which are determined upon are, to a certain extent, a matter of individual judgment, depending upon the field of illumination desired and upon the requirements of the law. In some cases it may be desirable to bend the light downward more than in others, and to secure a field of illumination which has its maximum intensity at a point nearer to the car than in other cases. There is, therefore, no intent to limit the invention to the particular range of angles illustrated and described, although such illustration and description are intended to indicate the best method of embodying the invention. As heretofore indicated, the bending downwardly of the rays transmitted through the upper portion of the lens is most important, so that a wider variation or departure from the construction illustrated is permissible in the lower portion of the lens than in the upper portion, although, as heretofore stated, it is desirable to bend the rays from this portion of the lens downward and particularly that portion transmitted nearest the center. The invention is also not limited to tilting an entire horizontal band at the same angle throughout, as in some cases it might be desirable to divide the band into a plurality of sections and tilt these sections differently.

What I claim is:

1. In combination in a headlight or cover glass for use with a parabolic reflector, a plate of glass having on one side a series of annular prisms, such prisms being divided into a plurality of horizontal bands with the

portions of the prisms in each band tilted about horizontal axes to turn the transmitted rays downwardly.

2. In combination in a headlight or cover glass for use with a parabolic reflector, a plate of glass having on one side a series of annular prisms, such prisms being divided into a plurality of horizontal bands with the portions of the prisms in each band similarly tilted about horizontal axes to turn the transmitted rays downwardly, but with varying angles of tilting for the different bands.

3. In combination in a headlight or cover glass for use with a parabolic reflector, a plate of glass having on one side a series of annular prisms, such prisms being divided into a plurality of horizontal bands with the portions of the prisms in each band similarly tilted about horizontal axes to turn the transmitted rays downwardly, but with varying angles of tilting for the different bands, and with the degree of tilting decreasing from the center of the lens up and down.

4. In combination in a headlight or cover glass for use with a parabolic reflector, a plate of glass having on one side a series of annular prisms of varying angles for bending the transmitted parallel rays from the reflector away from the axis thereof, such prisms being divided into a plurality of horizontal bands with portions of the prisms in each of such bands tilted at varying degrees about horizontal axes to turn the transmitted rays downwardly.

In testimony whereof, I have hereunto subscribed my name this 2nd day of February, 1921.

JACOB SODERBERG.
